UNITED STATES PATENT OFFICE.

JAMES M. HAMMOND, OF LANSING, MICHIGAN.

CATTLE-STALL.

SPECIFICATION forming part of Letters Patent No. 624,795, dated May 9, 1899.

Application filed March 28, 1898. Serial No. 675,435. (No model.)

To all whom it may concern:

Be it known that I, JAMES M. HAMMOND, a citizen of the United States, residing at Lansing, in the county of Ingham and State of Michigan, have invented certain new and useful Improvements in Cattle-Stalls; and I do hereby declare the following to be a full, clear, and exact description of the invention, such as will enable others skilled in the art to which it appertains to make and use the same.

My invention relates to certain new and useful improvements in cattle-stalls; and it has for its object to produce a stall which of its nature will be kept clean and sanitary.

15 A further object is to make such a stall readily accessible for the purpose of supplying food and drink to the occupant.

With these and other objects in view my invention consists in the novel details of construction and combination of parts to be fully described in the following specification and clearly set forth in the appended claims.

Referring to the accompanying drawings, forming part of this specification, in which like letters of reference indicate like parts throughout, Figure 1 is a longitudinal vertical section of my improved stall, showing an animal confined therein. Fig. 2 is a perspective view of the end of my stall, showing the feed-box withdrawn. Fig. 3 is an elevation of the front end of the stall. Fig. 4 is a sectional perspective view of the water-trough. Fig. 5 is a perspective view of the milking-seat in its folded position. Fig. 6 is a horizontal section 30 through the seat-post. Fig. 7 is a perspective view of the part shown in Fig. 5 in position for use, and Fig. 8 is an elevation of the milking-seat detached.

In the drawings, A represents a barn-floor, 40 partitioned off by side B and ends C into a number of stalls side by side in the usual manner. At the head of each stall is a water-trough D, running the full width of the stall and protected from dirt by an inclined cover E. Near 45 the end of this cover is a section hinged to the end C, forming a drop-lid F, having a projecting rounded edge by which the cow may lift it to drink from the trough and which will fall of its own weight to again completely 50 cover the trough when the cow is through drinking. On the other end of the trough is a box G for sulfur, salt, and the like, and

between the box and drop-lid I provide a hay-rack communicating with the loft above. (Not shown.) This hay-rack is formed by side 55 pieces H and a number of parallel inclined bars I, running from the front edge of the trough D to a horizontal beam, suitably supported on standards J.

Directly beneath the hay-rack is a U-shaped 60 feed-box K, with its curved front portion considerably lower than its rear and fitting closely against the curved strip L, which is secured to the floor. The feed-box is adapted to be introduced through a rectangular opening M in the end and close said opening with its rear portion when in position. I have provided the feed-box with a roller N on its rear edge that it may be easily moved from place to place, and the rear portion slants outward 65 at its upper edge, forming a chute O, to enable the feed-box to be filled without entirely withdrawing it.

A horizontal door P is hinged to the end C to open outward, and through this opening 75 the salt-box, water-trough, and hay-rack may be filled. Turn-buttons Q are secured to the end to engage the door P and the feed-box to lock them in position, and an eyebolt R is secured to the front of the trough, to which 80 the halter may be tied, as shown.

At the rear of the stall I provide an end strip S, projecting about four inches above the floor, and this end strip divides the stall from the floor of the alley T, which is somewhat lower than the floor of the stall. As 85 this end strip is very annoying for the animal to lie upon, it will be seen that she will always avoid it by reclining diagonally across the stall, thereby keeping herself clean of the 90 dirt in the alley, and I have so distanced the end strip from the hay-rack that she must necessarily have her hind feet in the alley when she stands upright, thus confining all droppings to the alley.

To one of the sides B, I attach an adjustable milking-seat U by means of a clip V, with a prong on one end, entering the standard at the end of the stall, and a screw passing through the other end, engaging the side B. A right- 95 angular rod W is journaled in the bearing formed between clip and the side B, and the seat U is secured to the horizontal arm of the rod W, so as to turn thereon that the seat and 100

rod may be folded out of the way against the side B, as shown in Fig. 5.

The advantages of such a stall as I have described will be apparent to all. The bedding of the animal is never contaminated with refuse matter, and consequently the animal is cleaner and healthier than she would otherwise be. The adjustable seat is very convenient for use, being stationary, and at the same time is never in the way, while the arrangement of the parts at the head of the stall besides being economical in having the feed-box in a position to catch the wastings from the hay-rack are convenient to manipulate from the outside.

It is obvious that many changes may be made in the construction described without departing from my invention.

Having thus fully described my invention, what I claim as new and useful, and desire to secure by Letters Patent, is—

1. A stall comprising side walls and an end wall, the latter provided with a base-opening, a floor elevated above the alley at the rear of the stall and separated therefrom by a fixed transverse end strip projecting above said floor, a cross-beam supported by standards, a water-trough secured to said end wall, a hay-rack composed of side pieces secured to the end wall and inclined bars connecting between

the cross-beam and trough, a horizontal door closing an opening in the end wall through which access to both the rack and trough is afforded from the exterior, and a removable feed-box accessible through the said base-opening in the end wall, substantially as described. 35

2. A stall comprising side walls and an end wall, the latter provided with a base-opening, a cross-beam supported by standards, a rack 40 arranged above said opening and having bars at the front thereof inclining downwardly and inwardly from the cross-beam, a curved strip extending between the standards at the bottom of the stall, and a feed-box adapted to be 45 inserted and withdrawn through the base-opening and to rest against said strip, said box comprising a U-shaped body highest at the rear and decreasing in depth toward its front end, a roller secured to the rear of the 50 box and holding the same inclined, and a back having an upwardly and outwardly slanting top edge forming a chute, substantially as described.

In testimony whereof I affix my signature 55 in presence of two witnesses.

JAMES M. HAMMOND.
